(57) **CLAIM**

The ornamental design for a wall rotary dryer, as shown and described.

DESCRIPTION

FIG. 1 is a top front left side perspective view of a wall rotary dryer in an open configuration showing my new design;

FIG. 2 is a front elevational view thereof;

FIG. 3 is a left side elevational view thereof, with the right side being a mirror image thereof;

FIG. 4 is a bottom plan view thereof;

FIG. 5 is a top front left side perspective view of the wall rotary dryer in a closed configuration;

FIG. 6 is a front elevational view of the wall rotary dryer of FIG. 5;

FIG. 7 is a left side elevational view of the wall rotary dryer of FIG. 5, with the right side being a mirror image thereof;

FIG. 8 is a top plan view of the wall rotary dryer of FIG. 5;

FIG. 9 is an enlarged bottom plan view of the wall rotary dryer of FIG. 5; and,

FIG. 10 is a bottom plan view of the wall rotary dryer of FIG. 1.
